DESIGN FOR A STAND FOR FLOWERS OR THE LIKE

Fritz Heidt, New York, N. Y.

Application June 7, 1944, Serial No. 113,894

Term of patent 3½ years

(Cl. D35—3)

To all whom it may concern:

Be it known that I, Fritz Heidt, a citizen of Germany, residing in New York, county and State of New York, have invented a new, original, and ornamental Design for a Stand for Flowers or the like, of which the following is a specification, reference being had to the accompanying drawing, forming part thereof.

I claim:

The ornamental design for a stand for flowers or the like, as shown.

FRITZ HEIDT.
